UNITED STATES PATENT OFFICE.

CASSIUS M. GAY, OF LOS ANGELES, CALIFORNIA.

REFRIGERATING APPARATUS.

1,156,525.

Specification of Letters Patent. Patented Oct. 12, 1915.

Application filed November 18, 1912. Serial No. 731,987.

To all whom it may concern:

Be it known that I, CASSIUS M. GAY, a citizen of the United States, residing at Los Angeles, in the county of Los Angeles, State of California, have invented certain new and useful Improvements in Refrigerating Apparatus, of which the following is a description, reference being had to the accompanying drawing, and to the figures 10 of reference marked thereon.

The invention relates to certain new and useful improvements in a refrigerating apparatus, and more particularly to devices of this character wherein the refrigerative effect is produced by the evaporating of water by a current of air passing over moistened surfaces.

An object of the invention is to provide a refrigerating apparatus wherein the air 20 circulating over the moistened surfaces is desiccated before it reaches the evaporative surfaces, where the final evaporation and cooling is effected.

A further object of the invention is to provide means in an apparatus of the above character for desiccating or dehydrating the air at atmospheric pressure and expanding the same over the moistened surfaces where the final evaporation and cooling is effected.

30 A still further object of the invention is to provide an apparatus of the above character wherein the air which is passed over the moistened surfaces for the final evaporation and cooling of the apparatus is first dehydrated by cooling the same as it passes through a chamber, the walls of which are moistened and subjected to a current of air.

A still further object of the invention is to provide an apparatus of the above character 40 wherein the air expelled from the refrigerating apparatus may be utilized for causing a circulation of the air through the auxiliary dehydrating device used for cooling the air passing through the moistened surfaces, where the final evaporation and cooling is effected.

These and other objects will in part be obvious, and will in part be hereinafter more fully disclosed.

50 In the drawings, which show by way of illustration one embodiment of the invention, Figure 1 is a vertical sectional view through a refrigerator, and an auxiliary dehydrating chamber embodying my invention; Fig. 2 is a side view of the same.

The invention consists generally of a refrigerator box or chamber proper constructed with an inner and outer shell or casing which are substantially imperforate. The inner shell is lined or covered on its outer surface with an absorbent material, which is supplied with moisture. Air is caused to circulate in a space between said inner and outer shells. This air is drawn from the refrigerator by a suitable air 65 pump. The supply pipe through which the air passes to the refrigerator is formed with a suitable valve, whereby the air space between the inner and outer shells may be maintained at slightly less than atmospheric pressure, so that the air will expand as it comes in contact with the moistened surfaces for evaporating the moisture and cooling the refrigerator.

The invention consists further in providing an auxiliary dehydrating or refrigerating device for desiccating or dehydrating the air which is utilized in the refrigerator box or chamber proper, for effecting the evaporation and cooling of the same. This 75 auxiliary dehydrator consists of an inner and outer casing in which the inner casing is covered on its outer face with an absorbent material, suitably moistened, and air is caused to circulate between said inner and outer casings by an ejector operated by the air discharged from the main refrigerator box or chamber. The air utilized for evaporating moisture in said main refrigerator passes through the inner casing of the auxiliary dehydrator, where it is cooled and the moisture contained therein collected on the surfaces of the casing, so that substantially dry air passes to the refrigerator proper.

90 Referring more in detail to the drawing, my improved apparatus consists of a main refrigerator box, herein shown as consisting of an inner shell or casing 1, and an outer shell or casing 2. Both of these casings are imperforate, except as hereinafter mentioned. The inner shell 1 is constructed preferably of galvanized iron, and is covered on its outer surface with asbestos, or some other suitable absorbent material, indicated at 3. This absorbent material is provided with moisture through supply pipes 4 and 5. The inner and outer shells are separated so as to form an air space 6. A partition 7 is located centrally of the outer casing, and terminates short of the bottom of 100 105 110

the casing, so as to divide the air space 6, whereby the air is caused to circulate entirely about the inner casing. The moisture supplied through the pipe 4 is directed to the casing at one side of the partition 7, while the moisture supplied through the pipe 5 is directed to the other side of the casing. The amount of moisture is regulated by suitable valves indicated at 8. At 10 the lower part of the outer casing 2 is a drain pipe 9, which is bent laterally and thence upwardly, as at 10, in order to form a suitable water seal. Air is delivered to the air space 6 through a pipe 11, and is withdrawn from the air space by a suitable exhaust fan or pump through a pipe 12. The receiving pipe is on one side of the partition 7, and the discharge pipe on the other. Therefore, the air passing through said 15 outer shell or casing will pass entirely about the inner shell or casing before it leaves through the discharge pipe. As above noted, the outer shell or casing is imperforate, except for the proper openings for the pipes 20 above mentioned. The exhaust fan or pump is located in the fan or pump casing 13, and said fan or pump may be operated by a suitable motor, located in a motor casing 14. The air is discharged from the pump 25 through a pipe 15.

In order that the storage compartment formed by the inner shell may be suitably ventilated, I have provided a by-pass pipe 16, which leads from the main pipe 11, and 30 a suitable valve 17 controls said by-pass pipe. This pipe 16 extends through both the inner and outer shells, and will deliver a certain amount of air to said inner compartment. The opposite side of said inner shell or casing is formed with an opening 18, which may be controlled by a suitable valve 19. This forms an outlet for the air delivered to the refrigerating compartment, so that the same may be suitably ventilated. It will, of course, be understood that the 35 proper doors are provided, whereby access may be had to said inner storage compartment.

The air which is passed to the main refrigerating box or chamber is first passed 40 through an auxiliary dehydrating or refrigerating device, consisting of an inner cylindrical casing 20, and an outer cylindrical casing 21, which is spaced therefrom, so as 45 to form an air-passage 22. This inner casing is provided on its outer face with an absorbent covering 23. Moisture is delivered to said absorbent covering through a pipe 24, which is controlled by a valve 25. At the upper end of the outer casing 21 is 50 a pipe 26, which is formed with a right-angle branch 27 and the pipe 15 has its discharge end tapered so as to restrict the delivering area thereof, and this tapered end 55 extends into said delivering pipe, so as to

form an ejector for drawing the air from the pipe 26 and through the air space 22, in the auxiliary refrigerating device. Both the inner and outer casings of the auxiliary refrigerating device are open at their lower 60 ends, so that the air may freely pass up through the same. This air is preferably at atmospheric pressure, and will cause the evaporation of the moisture in the absorbent or porous covering on the inner casing, 65 which will cool the same and the inner chamber 28 formed by said inner casing 20. The pipe 11 extends through the upper end of the outer casing 21, and connects with the chamber 28. Located centrally of the chamber 28 is a tube 29, to which is attached cone-shaped baffle plates 30. Between the cone-shaped baffle plates 30 are baffle plates 31, which are similarly shaped, but which are connected to the inner wall of the inner casing 20. These baffle plates will cause the air passing up through the chamber 28 to be thrown against the wall of the inner casing, where it will be cooled and dried, and the moisture contained in the air will collect on 70 said baffle plates and the inner wall of said cooled chamber. The water thus cooled will drain into the receptacles formed by the baffle plates 30, and the pipe is preferably 75 perforated, so as to drain these receptacles 80 and allow the water to pass out of the lower end of the pipe. The conveying pipe 11 is provided with a suitable valve 32, whereby the amount of air supplied relative to the amount of air exhausted may be varied, and thus pressure within the air space 6 of the main refrigerating box or chamber may be held slightly below atmospheric pressure, and the air delivered through the pipe 11 85 will, therefore, expand as it enters said air 90 space 6.

The operation of my refrigerating apparatus is as follows: The absorbent coverings of the main refrigerating chamber and the auxiliary refrigerating device are suitably 95 moistened, as above noted. The exhaust fan or pump in the chamber 13 is started, which operates to lower the pressure between the imperforate casings 1 and 2 of the main refrigerating device. The air so exhausted 100 by the fan or pump is discharged through the pipe 15, and the ejector formed at the end thereof, which causes a current of air to be drawn through the annular air passage 22 between the inner and outer cylinders or casings of the dehydrator. This air 105 passing over the moistened outer surface of the inner casing 20, and the atmospheric pressure cools the air within said casing and dries the same by subjecting said air to a 110 low temperature at atmospheric pressure. If the atmospheric air is close to the dew point, the cooled surface of the inner cylinder will precipitate the moisture, and thus 115 the air becomes dehydrated or desiccated be- 120 125 130 135

fore it passes the valve 32. The air, after passing the valve 32, will expand as the pressure in the air space 6 is somewhat below atmospheric pressure, and this expansion of the air which comes in contact with the moistened surface on the inner casing of the main refrigerating device greatly increases its evaporative efficiency. I am able thus to produce a multiplied effect of the refrigeration by first collecting and desiccating the air in the dehydrator, and then utilizing said dehydrated air expansively to produce evaporation in the main refrigerating chamber. Furthermore, by my improved apparatus, the refrigerating compartment is freely ventilated, which materially aids in the cooling thereof.

It is to be understood that the apparatus specifically described herein contains one embodiment of the invention only, and that said apparatus may be varied in many particulars, both as to details of construction and as to the arrangement of the parts without departing from the spirit of the invention, as set forth in the appended claims.

Having thus described my invention, what I claim is:

1. A refrigerating apparatus including in combination inner and outer casings forming an air space between the same, said inner casing being adapted to form a storage compartment and having an absorbent material on its outer surface, means for supplying moisture to said absorbent material, a dehydrator located outside of said outer casing, a conveyer pipe connecting said dehydrator to the air space between said casings and means for drawing air through the dehydrator and about said storage compartment.

2. A refrigerating apparatus including in combination inner and outer casings forming an air space between the same, said inner casing being adapted to form a storage compartment and having an absorbent material on its outer surface, means for supplying moisture to said absorbent material, a dehydrator located outside of said outer casing, a conveyer pipe connecting said dehydrator to the air space between said casings and means for drawing air through the dehydrator and about said storage compartment, said connecting means between the dehydrator and the air space having a valve therein whereby the air passing the valve may be caused to expand as it comes in contact with said moistened surface.

3. A refrigerating apparatus including in combination a main refrigerator having imperforate inner and outer casings, said inner casing having an absorbent material on its outer surface, means for supplying moisture to said absorbent material, means for supplying the air space between said inner and outer casings with desiccated air, and means

for exhausting the air from said air space, whereby said air is caused to expand as it comes in contact with said moistened surface.

4. A refrigerating apparatus including in combination a main refrigerator, having inner and outer casings, said inner casing being separated from said outer casing to form an air space, and having an absorbent material on its outer surface, means for supplying moisture to said absorbent material, a conveyer pipe for directing air to said air space, means for supplying said conveyer pipe with desiccated air, a valve in said conveyer pipe for regulating the supply, and an exhaust fan for withdrawing the air from said air space, whereby said air is caused to expand as it comes in contact with the moisture in said absorbent material.

5. A refrigerating apparatus including in combination a main refrigerator, having inner and outer casings, said inner casing being separated from said outer casing to form an air space, and having an absorbent material on its outer surface, means for supplying moisture to said absorbent material, a conveyer pipe for directing air to said air space, a valve in said conveyer pipe for regulating the supply, and an exhaust fan for withdrawing the air from said air space, whereby said air is caused to expand as it comes in contact with the moisture in said absorbent material, and an auxiliary refrigerating apparatus for cooling and desiccating the air which passes through said conveyer pipe.

6. A refrigerating apparatus including in combination a main refrigerator, having inner and outer casings, said inner casing being separated from said outer casing to form an air space and having an absorbent material on its outer surface, means for supplying moisture to said absorbent material, a conveyer pipe for directing air to said air space, a valve in said conveyer pipe for regulating the supply, and an exhaust fan for withdrawing the air from said air space, whereby said air is caused to expand as it comes in contact with the moisture in said absorbent material, and an auxiliary refrigerating device connected with said conveyer pipe for desiccating the air, said auxiliary refrigerating device consisting of an inner and outer casing spaced from each other and having an absorbent material on the outer surface of said inner casing, said conveyer pipe being connected to the chamber formed by said inner casing, and means for circulating air between said inner and outer casings, and over said moistened surface on said outer casing.

7. A refrigerating apparatus including in combination a main refrigerator, having inner and outer casings, said inner casing being separated from said outer casing to form

4
 in air space and having an absorbent material on its outer surface, means for supplying moisture to said absorbent material, a conveyer pipe for directing air to said air space, a valve in such conveyer pipe for regulating the supply, and an exhaust fan for withdrawing the air from said air space, whereby said air is caused to expand as it comes in contact with the moisture in said 10 absorbent material, and an auxiliary refrigerating device connected with said conveyer pipe for desiccating the air, said auxiliary pipe for desiccating the air, said auxiliary refrigerating device consisting of an inner and outer casing spaced from each other 15 and having an absorbent material on the outer surface of said inner casing, said conveyer pipe being connected to the chamber formed by said inner casing, a pipe leading from said air space between the inner and 20 outer casings of the auxiliary refrigerating device, and a pipe for utilizing the exhaust device, and a pipe for utilizing the exhaust from said fan to form an ejector for drawing the air through said last named pipe, and the auxiliary refrigerating device. 25 8. A refrigerating apparatus including in combination a main refrigerator, having inner and outer casings, said inner casing being separated from said outer casing to form an air space and having an absorbent material on its outer surface, means for sup-

plying moisture to said absorbent material, a conveyer pipe for directing air to said air space, a valve in said conveyer pipe for regulating the supply, an exhaust fan for withdrawing the air from said air space, whereby said air is caused to expand as it comes in contact with the moisture in said absorbent material, and an auxiliary refrigerating device connected with said conveyer pipe for desiccating the air, said auxiliary 35 refrigerating device consisting of an inner and outer casing spaced from each other and having an absorbent material on the outer surface of said inner casing, said conveyer pipe being connected to the chamber formed by said inner casing, and means for circulating air between said inner and outer casings, and over said moistened surface on said outer casing, said inner casing of said auxiliary refrigerating device having baffle 40 plates therein for directing the air to be desiccated against the cooled surface of said inner casing.

35
 In testimony whereof, I affix my signature, in the presence of two witnesses.
